UNITED STATES PATENT OFFICE.

WILLIAM M. THOMAS, OF ALBUQUERQUE, NEW MEXICO, ASSIGNOR OF THREE-TENTHS
TO A. W. GOODRICH AND FOUR-TENTHS TO C. M. BARBER, OF ALBUQUERQUE, NEW
MEXICO.

MOISTURE-SUPPLYING ATTACHMENT FOR INTERNAL-COMBUSTION ENGINES.

1,193,084.

Specification of Letters Patent.

Patented Aug. 1, 1916.

Application filed June 29, 1915. Serial No. 37,054.

To all whom it may concern:

Be it known that I, WILLIAM M. THOMAS, a citizen of the United States, residing at Albuquerque, in the county of Bernalillo, 5 State of New Mexico, have invented certain new and useful Improvements in Moisture-Supplying Attachments for Internal-Combustion Engines, of which the following is a specification.

10 My invention relates to new and useful improvements in mixing devices for internal combustion engines, the primary object of my invention being the provision of means for supplying moisture or moistened air to 15 the explosive mixture as it passes from the carbureter to the intake manifold of the engine.

A further object of the invention is the provision of a device of the above described 20 character which will not only supply moisture to the carbureted gas as it comes from the carbureter, but which will also thoroughly mix the carbureted gas and moist air before it enters the manifold.

25 In this connection, my invention comprehends a mixing device, claimed in a pending application filed by me December 14, 1915, Serial No. 66,759, adapted to be inserted between a carbureter and intake 30 manifold and a co-acting vaporizing cup adapted for connection between the water jacketing of the engine and the mixing device and capable of supplying moisture to the mixing device.

35 With these and other objects in view, my invention will be more fully described, illustrated in the accompanying drawings, then specifically pointed out in the claims which are attached to and form a part of this application.

40 In the drawings: Figure 1 is a side elevational view of a conventional form of internal combustion engine, showing my invention applied thereto; Fig. 2 is a vertical 45 sectional view taken through the mixing device; Fig. 3 is a section on the line 3-3 of Fig. 2; Fig. 4 is a perspective view of the various parts of the mixing device in unassembled position; Fig. 5 is a fragmentary view illustrating one manner of 50 securing the vaporizing cup to the engine casing; Fig. 6 is a central, vertical sectional view taken through the vaporizing cup.

Corresponding and like parts are referred

to in the following description and indicated in all the views of the drawings by the same reference characters.

55 My improved mixing device may be constructed as a part of the carbureter proper, as a part of the intake manifold of an internal combustion engine, or as an independent and detachable unit adapted to be interposed between the carbureter and manifold, the latter being the preferred method of construction.

60 The device includes a body portion 10, formed of metal or other suitable material and preferably either elliptical or rhombic shaped in plan view to correspond in general outline to the outline of the flanges 11 65 and 12 of the carbureter 13 and intake manifold 14, respectively, between which it is to be connected. For this purpose, it is provided adjacent its ends with bolt receiving bores by means of which bolts 15 may be applied to secure it in place, metallic gaskets or packing rings being usually interposed 70 between its faces and the flanges of the manifold and carbureter. This body member is provided centrally with a gas opening or 75 passage 16 substantially equal in diameter to the internal diameter of the outlet passage of the carbureter and the intake passage of the manifold and so disposed with respect to the bolt receiving openings as to extend in alignment with such passages and in effect form a continuation of them. As best 80 shown in Figs. 2 and 4 of the drawings, this passage, at its outlet end, is somewhat enlarged to provide a stop shoulder 17, for a 85 reason which will be later explained, and the passage, intermediate its length, is recessed or cut-away to form an annular chamber 18 completely surrounding it. The side wall of the body 10 is provided with a passage 19 communicating with the chamber 18 and tapped at its outer end to receive the 90 threaded end of a pipe 20 leading to a manually operable cut-off cock 21.

95 A metallic ring or sleeve 22 fits closely 100 within the passage 16 and closes the chamber 18, forming a wall therefor. This ring is provided at diametrically opposite points with openings to receive the ends of pipes or tubes 23 which, as a result, extend diametrically across the passage 16, these pipes, 105 where they cross each other, being either bent out of the way for that purpose or fit-

ted together in any suitable manner. That face of each pipe or tube which is directed toward the outlet end of the passage 16 is provided with a series of perforations 24 through which any moistened air admitted to the chamber 18 may be drawn by suction of the engine. In order to thoroughly mix the explosive mixture supplied from the carbureter with the moistened air supplied from the chamber 18, I provide a screen 25 of any suitable foraminous material, preferably fine wire gauze, which screen also serves as a filter, is generally reinforced peripherally by a metallic ring 26, the peripheral edge of the screen and ring seating against the shoulder 17, as best shown in Fig. 2.

A pipe 27 leads from the inlet port of the cut-off cock 21 to the outlet port of the vaporization cup 29. This cup includes a tubular body portion 30, preferably of glass, closed at its ends by flanged caps 31 and 32, suitable gaskets or packing rings 33, of rubber or other preferred material, being interposed to form tight joints. The caps 31 and 32 are provided with radially extending spaced ears 34 to receive tie bolts 35 which, with their nuts 36, provide means for clamping the caps against the ends of the tube 30. The cap 31 is formed with an internally threaded nipple 37 recessed to provide a semi-spherical valve seat 38 to receive a ball valve 39 carried by the end of a valve stem 40 which extends through a float 41 and is adjustably secured to the float by means of a nut 42 which is ordinarily so adjusted that a level of a quarter of an inch or more of water in the bottom of the cup will close the valve 39. The cap 32 is provided with a tapped opening 45 and any suitable type of union couplings 47 and 48 serve to connect the vaporization cup to the pipe 27 and to a pipe 49, the opposite end of which is threaded or otherwise connected to an opening formed in the water jacketing 50 of the engine, at any suitable point above the level of the cup 29.

In operation, the cut-off cock 21 is open to any suitable extent, dependent upon the amount of moistened air which the operator desires to supply to the manifold 14 and the engine then run in the usual manner. It will be clear that, due to the close proximity of the vaporization cup to the engine, the small amount of water contained therein will soon be heated and the steam or moist air thus generated will be drawn by the engine through the pipes 27 and 20 into the chamber 18 of the mixer and from this chamber through the perforated pipes or tubes 23 into the gas passage 16 and so, together with the explosive mixture from the carbureter, through the screen 25 to the manifold 14 and so to the engine cylinders. As the water contained in the vaporization

cup 29 is withdrawn in the form of vapor, the float 41 will fall, permitting opening of the valve 39 to admit fresh water from the water jacket 50.

By providing means for adding and thoroughly mixing moistened air with the explosive mixture from the carbureter, I prevent formation of carbon in the motor and upon the spark plugs and also increase the life of lubricating oil used in the cylinders and valves. As a result, the motor is smoother running and more powerful than would otherwise be the case.

My improved device may be readily attached to any motor vehicle gas engines now in use without any changes as practically all such engines are provided with one or more plug openings in their water jackets, the plug from which may be removed and replaced by a coupling for the pipe 49. The vaporization cup may be supported by any suitable form of bracket 43 formed with an eye to receive a bolt in the manner illustrated in Fig. 5. This bracket may be supported by one of the bolts 44 securing one of the valve cover plates in place or by one of the bolts connecting the engine cylinder housing to the crank case, as may be most convenient.

Having thus described the invention, what is claimed as new is:

1. The combination with an internal combustion engine having a water jacket, an intake manifold and a carbureter adapted to supply fuel to the intake manifold, of a vaporization cup, means for supplying water from the water jacket to the vaporization cup, means for limiting the amount of water in the cup, a mixer adapted to be inserted between the manifold and carbureter, and means for supplying moisture from the vaporization cup to the mixer, said mixer including a body having a fuel passage and an annular chamber surrounding the passage, a ring fitting in the passage and forming a wall for the chamber, and tubes communicating with the chamber through the ring and formed with perforations for the passage of moisture from the tubes to the manifold.

2. The combination with an internal combustion engine having a water jacket, an intake manifold and a carbureter adapted to supply fuel to the intake manifold, of a vaporization cup, means for supplying water from the water jacket to the vaporization cup, means for limiting the amount of water in the cup, a mixer adapted to be inserted between the manifold and carbureter, and means for supplying moisture from the vaporization cup to the mixer, said mixer including a body having a fuel passage and an annular chamber surrounding the passage, a ring fitting in the passage and forming a wall for the chamber, tubes communi-

cating with the chamber through the ring and formed with perforations for the passage of moisture from the tubes to the manifold, and a mixing screen interposed between the tubes and manifold.

3. A device of the character described including a vaporization cup provided at its lower end with an inlet port and at its upper end with an outlet port, means for connecting the inlet port with the water jacket of an engine, a float valve controlling the level of water admitted through the inlet port, a mixer adapted to be inserted between a carbureter and intake manifold, and means establishing communication between the outlet port of the cup and the mixer.
- 10 4. A device of the character described in-

cluding a vaporization cup provided at its lower end with an inlet port and at its upper end with an outlet port, means for connecting the inlet port with the water jacket of an engine, a float valve controlling the level of water admitted through the inlet port, a mixer adapted to be inserted between a carbureter and intake manifold, and means establishing communication between the outlet port of the cup and the mixer, said means including a manually operable valve.

In testimony whereof I affix my signature in presence of a witness.

WILLIAM M. THOMAS. [L. S.]
Witness:

A. W. GOODRICH.
